ABSTRACT OF THE DISCLOSURE

For protection against UV-radiation, particularly against radiation being in the range responsible for sunburn, compositions comprising compounds of the following formula as well as salts thereof:

wherein

R₁ represents H, CH₃ or C₆H₅,
R₂ and R₃ each represents H, alkyl of 1-12 carbon atoms, or together an alkylene chain of 3-4 carbon atoms,
R₄ and R₅ each represents H, alkyl of 1-12 carbon atoms, or together an alkylene chain of 3-4 carbon atoms,
R₆ to R₉ are the same or different and each represents H, SO₃H, alkyl of 1-12 carbon atoms; and the salts thereof, said salts being selected from the group consisting of sodium, potassium, mono-, di-, and triethanolammonium salts. Particularly effective compounds are 2-benzoyl-3-methyl-benzofuran, and 2-(2,4-dimethyl-benzoyl)-benzofuran.

This invention relates generally to a group of chemical compounds which are particularly useful as UV absorbents, and more particularly, to the use of these compounds in cosmetics to substantially eliminate the harmful effects of UV radiation.

Oxerexposure of the skin to ultraviolet rays within the ultraviolet range of about 290-320 m μ produces radiation burns or erythema. When the sun is the radiation source, the resulting burning of the skin is known as sunburn. To afford maximum protection against erythema or sunburn, an agent which is a strong absorber of UV radiation is desirably applied to the exposed skin.

It is, therefore, a principal object of this invention to provide novel and unobvious chemical compounds.

Another object is to provide processes for the production of these novel and unobvious compounds.

A still further object is to provide cosmetic compositions which are resistant to UV radiation.

Still another object is to provide a process of administering the cosmetic compositions of this invention to mammals to prevent sunburn.

Upon further study of the specification and claims, other objects and advantages of the present invention will become apparent.

2

These objects are attained on the basis of the following compounds of Formula I:

wherein:

R₁ is H, CH₃, or C₆H₅,

R₂ to R₅ are the same or different and each represent H, alkyl having 1 to 12, preferably 1 to 4 carbon atoms, more preferably methyl, or the radical combinations selected from the group consisting of R₂ and R₃, and R₃ and R₄ form a single alkylene chain having 3 to 4 carbon atoms, and

R₆ to R₉ are the same or different and each represent H, SO₃H, or alkyl having 1 to 12, preferably 1 to 4 carbon atoms, and the salts thereof, preferably their sodium, potassium, mono-, di- or triethanolammonium salts.

It was unexpectedly discovered that the compounds of Formula I and the salts thereof absorb, with low transmittance, UV radiation in the range of about 290-320 m μ which is primarily responsible for the symptoms of burning of human skin.

The excellent UV absorption of the compounds of this invention are shown in the following table wherein the percent transmission of the compounds (A) 2-benzoyl-3-methyl-benzofuran, and (B) 2-(2,4-dimethylbenzoyl)-benzofuran are tabulated as a function of wavelength λ . The transmission is based on a 2% concentration of these compounds in a methanol solution, measured at a layer thickness of 0.005 mm.

In m μ	Percent transmissivity	
	A	B
280	49.8	34
290	35.6	23
300	22.9	16
310	15.1	12
320	13.6	18
330	22.6	44
340	48.1	77
350	73.6	86

It can be seen in the above table that UV radiation harmful to the skin and in the range between 290 and 320 m μ is effectively absorbed, while radiation above 330 m μ which promotes tanning penetrates the protective coating. The other compounds of Formula I exhibit similar transmissivity values.

The compounds of this invention are particularly suitable for cosmetic applications wherein it is desired to reduce the transmittance of UV radiation in the range of 290-320 m μ .

The compounds of this invention are particularly suitable for use in cosmetics which are designed to protect the skin from the sun, e.g. to avoid formation of freckles. Moreover, by using a weak concentration on skin exposed to the sun, tanning of the skin is promoted without sacrifice of the protection afforded against sunburn and erythema. In cosmetic compositions there are generally employed about 0.5 to 10%, preferably 1 to 5% of active UV absorber by weight of the total composition.

Many of the commercially available UV absorbents such as ethoxyethyl p-methoxycinnamate and methyl or

glyceryl p-dimethylaminobenzoate contain ester groups which can decompose under extreme conditions. The effectiveness of the compounds of this invention, however, remains unimpaired under extreme conditions because of the lack of such ester groups.

In addition to the selective absorption and excellent stability of the compounds of this invention, they are further distinguished by their low toxicity, high resistance to light and to atmospheric conditions, and their odorlessness.

From among the compounds found suitable for use as UV absorbents, the following groups of compounds are preferred, referring to Formula I:

(A) compounds wherein

R_1 is hydrogen,
 R_2 to R_5 have the previously indicated meaning, and
 R_6 to R_9 represent H, or only one group is SO_3H .

(B) compounds wherein

R_1 , R_3 and R_5 are H,
 R_2 and R_4 are the same or different and each represent H, or CH_3 , and
 R_6 to R_9 represent H, or only one of these groups is SO_3H .

(C) compounds wherein

R_1 is CH_3 , phenyl, or H when at least one of the groups R_6 to R_9 is alkyl of 1-12 carbon atoms,
groups R_6 to R_9 is alkyl of 1-12 carbon atoms,
 R_2 to R_5 have the previously indicated meaning, and
 R_6 to R_9 represent H, SO_3H , or alkyl of 1-12 carbon atoms, preferably methyl.

(D) compounds wherein

R_1 is CH_3 ,
 R_2 is H, or CH_3 ,
 R_3 and R_5 are H,
 R_4 is H, or alkyl of 1-12 carbon atoms,
 R_6 , R_8 , and R_9 are H, or one of them SO_3H , and
 R_7 is H, or alkyl of 1-12 carbon atoms.

(E) compounds wherein

R_1 to R_5 have the previously indicated meaning, and
 R_6 to R_9 represent H, alkyl of 1-12 carbon atoms, preferably methyl, with the provision that one of R_6 to R_9 is SO_3H .

(F) compounds wherein

R_1 to R_5 have the previously indicated meaning, and
 R_6 to R_9 represent H, or alkyl of 1-12 carbon atoms, and the salts of the compounds of (A) to (E), preferably their sodium, potassium, mono-, di-, or triethanolammonium salts.

In addition to methyl, the following are preferred alkyl substituents of the benzene ring of the benzofuran system, or at the phenyl ring: ethyl, propyl, isopropyl, n-butyl, isobutyl, sec.-butyl, tert.-butyl, n-amyl, isoamyl, n-hexyl, n-heptyl, n-octyl, n-nonyl, n-decyl, n-undecyl and n-dodecyl. Desirably, there can also be a tetrahydro-naphthyl-(5)- or -(6)- or an indanyl-(4)- or -(5)-radical on the carbonyl group instead of on the phenyl ring.

The compounds of Formula I which are particularly suitable are:

2-benzoyl-benzofuran.

2-(2,4-dimethylbenzoyl)-benzofuran, boiling point 190° C./1 mm.

2-(4-methylbenzoyl)-benzofuran.

2-(4-isopropylbenzoyl)-benzofuran, M.P. 105-107° C.

2-(tetrahydronaphthoyl-2)-benzofuran, M.P. 58-60° C.

2-(4-tert.butylbenzoyl)-benzofuran, M.P. 122-124° C.

2-(3,4-dimethylbenzoyl)-benzofuran, M.P. 101-103° C.

2-(2,3,5-trimethylbenzoyl)-benzofuran, boiling point 260-265° C./12 mm.

2-(2-isopropyl-5-methylbenzoyl)-benzofuran, boiling point 280-290° C./20 mm.

2-benzoyl-3-methyl-benzofuran, M.P. 51-52° C.

2-(2,4-dimethylbenzoyl)-3-methyl-benzofuran, boiling point 225-228° C./12 mm.

2-(4-methylbenzoyl)-3-methyl-benzofuran, boiling point 224-226° C./12 mm.

2-(4-dodecylbenzoyl)-3-methyl-benzofuran, boiling point 305-310° C./12 mm.

5 2-benzoyl-3,5-dimethyl-benzofuran, M.P. 81-83° C.

2-benzoyl-3-methyl-5-nonyl-benzofuran, boiling point 265-275° C./12 mm.

2-benzoyl-3-phenyl-benzofuran.

2-benzoyl-5-methyl-benzofuran, as well as the sulfonic acid derivatives thereof, especially

10 2-benzoyl-benzofuran sulfonic acid, and

2-benzoyl-3-methyl-benzofuran sulfonic acid (the sulfonic acid group being presumably located at position 5 of the benzofuran system) and their salts, preferably the sodium salts.

15 The compounds of this invention are provided for all types of applications and in all types of cosmetic compositions in which UV absorbents are conventionally employed.

20 Thus, for example, it is possible to incorporate the compounds of this invention in lotions, emulsions, salves, creams, aerosols, and the like, which are usually employed for topical administration to humans. Such cosmetic compositions for topical administration can be described as

25 having a form ranging from a liquid to thixotropic non-Newtonian liquids, to semi-solids such as pastes, to oily solids having, for example, a consistency like butter.

The compounds of this invention lacking sulfonic acid groups are soluble in mineral oils, vegetable oils, and fats, e.g. in liquid paraffin or saturated fatty acid triglycerides. The compounds of Formula I which do contain a sulfonic acid group, particularly 2-benzoyl-3-methyl-benzofuran sulfonic acid and its salts, preferably its sodium, potassium, monoethanolammonium-, diethanolammonium and triethanolammonium salts, are easily soluble in water.

35 The choice of carrier for these compounds depends therefore, on whether a sulfonic acid group is present. Generally, however, carriers usually associated with UV-resistant cosmetic preparations can be employed, such as

40 solid or liquid paraffin, ceresin, mineral wax; vegetable or animals oils and fats such as olive oil, peanut oil, sesame oil or almond oil; cocoa butter, beeswax, mineral wax or carnauba wax, wool fat, spermaceti; fatty acids and fatty acid esters such as stearic, palmitic and oleic acids, glycerin mono- or distearates, glycerin monooleate, isopropyl myristate, isopropyl stearate, butylstearate; ethyl, isopropyl, cetyl, stearyl and palmityl alcohols; wetting agents of multivalent alcohols such as glycol, glycerin, sorbitol; emulsions of oil in water or water in oil systems, utilizing emulsifying agents (ionic, nonionic, cationic anionic, or ampholytic); thickeners such as methyl, ethyl or carboxymethyl cellulose, polyacrylic acid, tragacanth, agar-agar, gelatine. Further additives such as perfumes, preservative, or physiologically compatible dyestuffs can also be incorporated.

50 45 55 The UV absorbents of this invention can, if desired, be used in combination with one or more of the conventional UV absorbents, such as 2-phenylbenzimidazol-5-sulfonic acid-sodium salt, 3,4-dimethylphenylglyoxylic acid sodium salt, 4-phenylbenzophenone, isoctyl-4-phenylbenzophenone-2'-carboxylate.

The compounds of Formula I lacking a sulfonic acid group are obtained by the conventional reaction, in the presence of aluminum chloride, of the respective benzofuran-2-carboxylic acid chloride (such as benzofuran-2-carboxylic acid chloride, 3-methyl-, 3,5-dimethyl-, 3-methyl-5-nonyl-, 3-phenyl- or 5-methyl-benzofuran-2-carboxylic acid chloride), or the corresponding bromides with benzene or alkylbenzenes such as toluene, o-, m- or

60 65 70 p-xylene, cumene, p-cymene, tert.-butylbenzene, indane or Tetraline.

75 Alternatively, these compounds can be obtained by the reaction of the sodium salts of salicylic aldehydes or o-hydroxyphenylketones (such as salicylaldehyde, 5-methylsalicylaldehyde, o-hydroxyacetophenone, 2-hydroxy-5-

H, SO₃H, or alkyl of 1-12 carbon atoms; and the salts thereof, said salts being selected from the group consisting of sodium, potassium, mono-, di-, and triethanolammonium salts.

2. A composition as defined by claim 1 wherein said compound is selected from the group consisting of 2-benzoyl-benzofuran; 2-benzoyl-3-methyl-benzofuran; 2-(2,4-dimethylbenzoyl)-benzofuran; 2-(2,4-dimethylbenzoyl)-3-methyl-benzofuran and mixtures thereof.

3. A composition as defined by claim 1 wherein

R₁ is CH₃, phenyl, or H when at least one of the groups R₆ to R₉ is alkyl of 1-12 carbon atoms, R₂ to R₅ have the previously indicated meaning, and R₆ to R₉ represent H or alkyl of 1-12 carbon atoms.

4. A composition as defined by claim 1 wherein

R₁ is CH₃,

R₂ is H, or CH₃,

R₃ and R₅ are H,

R₄ is H, or alkyl of 1-12 carbon atoms,

R₆, R₈ and R₉ represent H or SO₃H, and

R₇ is H, or alkyl or 1-12 carbon atoms.

5. A composition as defined by claim 1 wherein

15

R₁ to R₅ have the previously indicated meaning, and R₆ to R₉ represent H, alkyl of 1-12 carbon atoms, with the provision that one of R₆ to R₉ is SO₃H.

6. A composition as defined by claim 1 wherein said compound is selected from the group consisting of 2-benzoyl-3-methyl-benzofuran, 2-(2,4-dimethylbenzoyl)-benzofuran, 2-(2,4-dimethylbenzoyl)-3-methyl-benzofuran, 2-benzoyl-3,5-dimethylbenzofuran, 2-benzoyl-3-methyl-5-nonyl-benzofuran, and 2-benzoyl-3-phenyl-benzofuran.

7. A process for decreasing the effect of UV radiation on mammalian skin, which process comprises topically administering a composition as defined by claim 1.

10 8. A process for decreasing the effect of UV radiation on mammalian skin, which process comprises topically administering a composition as defined by claim 2.
